TREATMENT OF HYDROCARBONS

Aristid V. Gresse, Bronxville, N. Y., and William J. Mattox, Chicago, Ill., assignors to Universal Oil Products Company, Chicago, Ill., a corporation of Delaware

Application January 8, 1940, Serial No. 312,832

4 Claims. (Cl. 260—673.5)

This invention relates particularly to the conversion of straight chain hydrocarbons into closed chain or cyclic hydrocarbons.

More specifically it is concerned with a process involving the use of particular catalysts and specific conditions of operation in regard to temperature, pressure, and time of reaction whereby aliphatic hydrocarbons can be converted efficiently into aromatic hydrocarbons.

In the production of aromatic hydrocarbons from paraffins by dehydrocyclization, certain amounts of olefinic hydrocarbons are formed simultaneously, and in the cycling of olefinic hydrocarbons, the product contains not only aromatic hydrocarbons but also unchanged olefins. In each of these cases part of these olefins cannot be separated readily by fractional distillation or by solvent extraction, but they must be removed in some way if the aromatics are to be used for nitration or for other chemical work requiring pure aromatic hydrocarbons or substantially olefin-free aromatic-containing hydrocarbon mixtures. The conversion of these olefins to paraffins by hydrogenation or their removal by acid absorption or by oxidation are expensive operations and result in considerable loss of materials. The process of this invention converts these olefins into aromatics and produces a relatively high yield of substantially olefin-free aromatic hydrocarbons.

In one specific embodiment the present invention comprises a process for producing aromatic hydrocarbons from aliphatic hydrocarbons including paraffins and olefins which comprises contacting said aliphatic hydrocarbons under dehydrocyclizing conditions of temperature and pressure with a composite comprising essentially a major proportion of a substantially inert refractory carrier and a relatively minor proportion of an oxide of an element selected from the members of the left-hand columns of groups 4, 5, and 6 of the periodic table to form a product containing aromatic, olefinic, and paraffinic hydrocarbons; extracting said product by a selective solvent to separate a mixture comprising essentially olefinic and aromatic hydrocarbons from a substantially paraffinic raffinate; recovering and recycling said solvent to further extraction use; recycling said paraffinic raffinate to the original dehydrocyclizing zone; and conducting said mixture of olefinic and aromatic hydrocarbons to a second dehydrocyclizing zone to produce a substantially olefin-free aromatic product.

According to the present invention aliphatic or straight chain hydrocarbons having 6 or more

carbon atoms in straight chain arrangement in their structure are specifically dehydrogenated in such a way that the chain of carbon atoms undergoes ring closure with the production in the simplest case of benzene from n-hexane or n-hexene and in the case of higher molecular weight paraffins of various alkyl derivatives of benzene. Under properly controlled conditions of temperature, pressure, and time of contact, very high yields of the order of 75 to 90% of the benzene or aromatic compounds are obtainable which are far in excess of any previously obtained in the art either with or without catalysts. For the sake of illustrating and exemplifying the types of hydrocarbon conversion reactions which are specifically accelerated under the preferred conditions by the present types of catalysts, the following structural equations are introduced:

Ethyl benzene and o- and m-xylene are also formed from n-octane by a combination of reactions involving dehydrogenation, cyclization, and isomerization, but no idea is offered as to the probable order in which these reactions occur.

In the foregoing table the structural formula of each of the primary paraffin hydrocarbons has been represented as a nearly closed ring instead of by the usual linear arrangement for the sake of indicating the possible mechanisms involved. No attempt has been made to indicate the possible intermediate existence of mono-olefins, di-olefins, hexamethylenes, or alkylated hexamethylenes which might result from the loss of various amounts of hydrogen. It is not known at the present time whether ring closure occurs at the loss of one hydrogen molecule or whether dehydrogenation of the chain carbons occurs so that the first ring compound formed is an aromatic

such as benzene or one of its derivatives. The above three equations are of a relatively simple character indicating generally the type of reactions involved but in the case of n-paraffins or mono-olefins of higher molecular weight than the octane shown and in the case of branch chain compounds which contain various alkyl substituent groups in different positions along the 6-carbon atom chain, more complicated reactions will be involved. For example, in the case of such a primary compound as 2,3-dimethyl hexane the principal resultant product is apparently o-xylene although there are concurrently produced definite yields of such compounds as ethyl benzene indicating an isomerization of two substituent methyl groups. In the case of nonanes which are represented by the compound 2,3,4-trimethyl hexane, there is formation not only of mesitylene but also of such compounds as methyl ethyl benzene and various propyl benzenes.

It will be seen from the foregoing that the scope of the present invention is preferably limited to the treatment of aliphatic hydrocarbons which contain at least 6 carbon atoms in straight chain arrangement. In the case of paraffin hydrocarbons containing less than 6-carbon atoms in linear arrangement, some formation of aromatics may take place due to primary isomerization reactions although obviously the extent of these will vary considerably with the type of compound and the conditions of operation. The process is readily applicable to paraffins from hexane up to dodecane and their corresponding olefins. With increase in molecular weight beyond this point the percentage of undesirable side reactions tends to increase and yields of the desired alkylated aromatics decrease in proportion.

While any suitable type of catalyst having dehydrogenating and cycling properties may be employed for converting paraffins into substantial yields of aromatics, according to this invention, a satisfactory catalytic material comprises a major proportion of a refractory spacing agent, carrier, or support selected from the group consisting of alumina, magnesia, silica, diatomaceous earth, and activated clay and a relatively minor proportion of an oxide of an element or a combination of oxides of elements selected from members of the left-hand columns of groups 4, 5, and 6 of the periodic table consisting of titanium, zirconium, cerium, hafnium, and thorium; vanadium, columbium, and tantalum; chromium, molybdenum, tungsten, and uranium.

The carriers or supports referred to above have relatively low catalytic activities while the oxides of the elements mentioned are of relatively high catalytic activity and furnish by far the greater proportion of the observed catalytic effects. The oxides of these several elements vary somewhat in catalytic activity in any given reaction comprised within the scope of the invention and this variation may be greater in the case of different types of dehydrogenation and cyclization reactions.

In regard to the preparation of alumina which is generally preferable as a carrier or support for the preparation of dehydrocycling catalysts, it may be stated that three hydrated oxides of aluminum occur in nature, to wit, hydrargillite or gibbsite having the formula $Al_2O_3 \cdot 3H_2O$, bauxite having the formula $Al_2O_3 \cdot 2H_2O$, and diasporite, having the formula $Al_2O_3 \cdot H_2O$. Of these three minerals the corresponding oxides from the trihydrated and dihydrated minerals are suitable

for the manufacture of the present types of catalysts and these materials have furnished types of activated alumina which are entirely satisfactory. Precipitated trihydrates can also be dehydrated at moderately elevated temperatures to form satisfactory types of alumina. Crystallographically and X-ray spectroscopically, this most satisfactory type of alumina is referred to as gamma-alumina, crystallizing in the cubic system, the length of the edge of the unit cube being about 7.90 Angstrom units. Alumina in the form of powdered corundum or prepared by dehydrating diasporite is not suitable.

It is best practice in the final steps of preparation of aluminum oxides for use in the catalyst composites to ignite them for some time at temperatures within the approximate range of 900-1050° F. This does not correspond to complete dehydration of the hydrated oxides but gives catalytic materials of good strength and porosity so that they are able to resist for a long period of time the deteriorating effects of the service and reactivation periods to which they are subjected.

25 The catalytic dehydrogenating efficiency of alumina is greatly improved by the presence of oxides of the preferred elements in relatively minor amounts. The oxides which constitute the principal active catalytic materials may be deposited upon the surface and in the pores of the activated alumina granules by several alternative methods, such as, for example, the ignition of nitrates which have been absorbed or deposited from aqueous solution by evaporation or by a similar ignition of precipitated hydroxides. As an alternative method, though obviously less preferable, the finely divided oxides may be mixed mechanically with the alumina granules either in the wet or dry condition. The point of achieving 30 the most uniform practical distribution of the oxides on the alumina should constantly be borne in mind since the observed catalytic effects evidently depend principally upon surface action.

45 While dehydrogenation of aliphatic hydrocarbons may be effected in the presence of a large number of carriers supporting members of a relatively large group of oxides as hereinabove indicated, oxides of a few metals of this group have been found, in general, to be more useful than others either as individual oxides, as mixtures of oxides of a particular metal, or as mixtures of any combination of oxides of the elements vanadium, chromium, and molybdenum. Methods of preparing dehydrogenating and cycling 50 catalysts containing oxides of these elements are described in later paragraphs of this specification.

The oxide of vanadium which results from the ignition of the nitrate, the hydroxide, or the carbonate is principally the pentoxide V_2O_5 which is reduced by hydrogen to form the tetroxide V_2O_4 , or the corresponding dioxide VO_2 and then to the sesquioxide V_2O_3 . In any case the primary deposition of vanadium compounds upon alumina granules may be made by the use of the soluble vanadyl sulfate or the nitrate and also solutions of ammonium and alkali metal vanadates may be employed, which furnish alkaline residues on ignition. It is probable that the sesquioxide is the principal compound which accounts for the catalytic activity observed with vanadium catalysts in reactions of the present character.

70 The element chromium has three oxides, the trioxide Cr_2O_3 , the dioxide CrO_2 , and the sesquioxide Cr_2O_3 , the last named being readily produced by heating the trioxide in hydrogen or

hydrocarbon vapors at a temperature of 480° F. The dioxide has been considered to be an equimolecular mixture of the trioxide and the sesquioxide. The oxides are readily developed on the surfaces and pores of alumina or other carrier granules by utilizing primary solutions of chromic acid H_2CrO_4 or chromium nitrate $Cr(NO_3)_3$. The ignition of the chromic acid, the nitrate, or the precipitated trihydroxide produces primarily the trioxide which is then reduced to the sesquioxide to furnish an active catalyst for use in reactions of the present character.

The two most important oxides of molybdenum which are employed alternatively in the production of dehydrocyclization catalysts, according to the present invention, are the dioxide MoO_2 and the sequioxide Mo_2O_3 . Since the reduction of the trioxide by hydrogen begins at about 570° F. and the reduction is rapid at 840° F. the effective catalytic material is principally the sesquioxide. The trioxide may be added to the active alumina carrier from a solution in aqueous ammonia or from a solution of ammonium molybdate which is added in amounts just requisite to wet the carrier granules uniformly and the mass is then dried and calcined.

It has been found essential in the production of high yields of aromatic from paraffinic and olefinic hydrocarbons when using the preferred types of dehydrocyclization catalysts that, depending upon the aliphatic hydrocarbon or mixture of aliphatic hydrocarbons being treated, temperatures from 850 to 1200° F. should be employed, contact times of approximately 0.1 to 60 seconds, and pressures approximating atmospheric. The use of sub-atmospheric pressure of the order of $\frac{1}{4}$ atmosphere may be beneficial in that reduced pressure generally favors selective dehydrogenation reactions, but on the other hand moderately superatmospheric pressure usually of the order of less than 100 pounds per square inch, increases the capacity of commercial plant equipment, so that in practice a balance is struck between these two factors.

It will be appreciated by those familiar with the art of hydrocarbon conversion in the presence of catalysts that the factors of temperature, pressure, and time will frequently need to be adjusted upon the basis of preliminary experiments to produce the best results in any given instance. The criterion of the yield of aromatics will serve to fix the best conditions of operation and in general the relations between temperature, pressure, and time are adjusted preferably so that rather intensive conditions are employed of sufficient severity to insure a maximum amount of the desired cyclization reactions with a minimum of undesirable side reactions. If the times of catalytic contact employed are too short the conversion reactions may not proceed beyond those of simple dehydrogenation and the yields of olefins and diolefins will predominate over those of aromatics.

Among the solvents which may be used for separating products of dehydrocyclization reactions into mixtures comprising essentially aromatic and olefinic hydrocarbons from paraffinic hydrocarbons are sulphur dioxide, furfural, nitrobenzene, phenol, cresol, β,β -dichloroethylether, methylcarbitol, and others which have selective solvent effects and which are capable of being recovered by one of several well known methods. Such methods of solvent recovery include distillation where the extracted oil and the solvent boil within different ranges, and the precipitation of the sol-

vent by the addition of another material, as water, which renders the solvent and extracted oil mutually immiscible.

For the purpose of illustrating the process of the present invention, the attached drawing shows diagrammatically a typical process flow for producing aromatic hydrocarbons from paraffinic hydrocarbons containing a chain of 6-12 carbon atoms per molecule.

Referring to the drawing an aliphatic hydrocarbon fraction comprising essentially paraffins and olefins containing 6-12 carbon atoms per molecule is introduced through line 1 to dehydrocyclization zone 2 which may comprise a chamber or a plurality of chambers containing a granular dehydrocyclization catalyst maintained under conditions of temperature, pressure, and time adequate to effect substantial formation of aromatic hydrocarbons and relatively minor production of olefinic hydrocarbons by dehydrogenation and cycling reactions. Dehydrocyclization zone 2 may also include preheating equipment in which the aliphatic hydrocarbons charged are heated to a dehydrocyclization temperature before being admitted to the reactors containing the granular catalyst.

The dehydrocyclization products consisting of hydrogen, other light gases, aromatic hydrocarbons, and unconverted paraffinic and olefinic hydrocarbons are conducted from dehydrocyclization zone 2 through line 3 to separation zone 4 from which gaseous products are discharged through line 5.

Normally liquid hydrocarbons consisting of paraffins, olefins, and aromatics are conducted from separation zone 4 through line 6 to extraction zone 7 in which a mixture of aromatic and olefinic hydrocarbons is extracted from paraffinic hydrocarbons. This extraction of aromatic and olefinic hydrocarbons from paraffinic hydrocarbons may be made either by batch or continuous processes although from the standpoint of efficiency the method of counterflow extraction is preferable in common operations. The details of the batch and counter-flow procedures are generally well known in common practice and need not be enlarged upon here since they form no special feature of the present invention.

From extraction zone 7 a raffinate comprising essentially paraffinic hydrocarbons is conducted through line 8 and recycled by way of line 1 to further treatment in dehydrocyclization zone 2.

Before this raffinate is recycled it may be necessary to remove relatively small amounts of solvent contained therein. For example when sulphur dioxide is the solvent it may be desirable to wash the raffinate with water and/or caustic soda solution and dry the same before it is returned to further dehydrocyclization treatment.

From solvent extraction zone 7 the solution containing dissolved olefins and aromatic hydrocarbons may be withdrawn through line 9 to separation zone 10 in which the hydrocarbons are separated from the solvent. Recovered solvent is conducted from separation zone 10 through line 11 and recycled through line 6 to further use in extraction zone 7. Fresh solvent may be introduced to line 6 as desired through line 12, while used and recovered solvent may be withdrawn from line 11 by way of line 13. The nature of separation zone 10 is dependent upon the solvent employed. In case the preferred solvent is sulphur dioxide, it may be separated by fractional distillation from the aromatic and olefinic hydrocarbons dissolved therein followed by washing of

the hydrocarbon product to remove the relatively small amounts of solvent present.

The mixture of aromatic and olefinic hydrocarbons separated from the selective solvent in separation zone 10 is conducted thence through line 14 to a second dehydrocyclizing zone 15 containing granular dehydrocyclizing catalyst and operated at conditions of temperature, pressure, and time adequate to effect substantially complete conversion to aromatics of the olefinic hydrocarbons present in the product obtained from the first dehydrocyclization step. Thus the aromatic-olefinic extract containing relatively minor proportions of olefins is subjected to further cycling in contact with essentially the same type of dehydrocyclizing catalyst such as 2-25% chromium sesquioxide on alumina at a temperature in the approximate range of 825-1200° F. under substantially atmospheric pressure for an average time in the range of 1-100 seconds. Under these conditions the aromatics undergo substantially no decomposition while the smaller quantities of olefins contained in the extract are converted to aromatic hydrocarbons. Reaction products are withdrawn from dehydrocyclizing zone 15 through line 16 to separation zone 17 from which gaseous products are discharged through line 18 and substantially pure aromatic hydrocarbons are withdrawn through line 19 to storage.

The catalytic process herein described makes possible the conversion of aliphatic hydrocarbons into pure aromatics or aromatic mixtures which are free from olefins and suitable for nitration or for other chemical reactions or uses where olefins are objectionable. Also by this process the olefins contained in the products of the first cyclization stage are converted further to aromatics in the second stage so that the yield of aromatic hydrocarbons is increased considerably over that obtainable by dehydrocyclization in a single stage.

The following example is introduced to show results obtainable in the operation of the process although these data are not presented with the intention of limiting unduly the broad scope of the invention.

A mixture of 75 mole per cent paraffinic and 25 mole per cent olefinic hydrocarbons boiling within the range of 150-400° F. was passed at 1050° F. under atmospheric pressure through a tube containing a layer of 3 x 3 mm. pellets formed from a composite consisting of 12% chromium sesquioxide and 88% activated alumina. When the hydrocarbon mixture was charged at a rate corresponding to an average contact time of 2 seconds, the product of this treatment contained 60% aromatics, 20% olefins, and 20% paraffins. The paraffins, separated from the olefins and aromatics by extraction with liquid sulphur dioxide, were recycled to the original dehydrocyclizing zone while the extracted hydrocarbons after removal and re-use of the sulphur dioxide solvent were conducted to a second catalyst reactor containing another portion of the 12% chromium sesquioxide on alumina catalyst at 1150° F. under atmospheric pressure using a charging rate corresponding to an average contact time of 5 seconds. The latter treatment gave relatively small amounts of hydrogen and other gaseous products and produced a normally liquid aromatic fraction substantially free from olefinic hydrocarbons and suitable for nitration use.

The foregoing specification and example show clearly the character of the invention and the

results to be expected in its application to aliphatic hydrocarbons including paraffins and olefins although neither section is intended to be unduly limiting.

5 We claim as our invention:

1. A process for the production of aromatic hydrocarbons from aliphatic hydrocarbons having 6-12 carbon atoms to the molecule which comprises subjecting the hydrocarbon to contact with 10 a dehydrocyclizing catalyst under dehydrocyclizing conditions of temperature and pressure, subjecting the resulting conversion products comprising aromatics, olefins and paraffins to the action of 15 a solvent to effect the separation of a paraffinic raffinate and an extract comprising olefins and aromatics, and subjecting said extract to contact with a separate dehydrocyclizing catalyst under independently controlled conditions of temperature and pressure to form a substantially olefin-free aromatic product.

2. The process of claim 1 further characterized in that said raffinate is subjected to further treatment in contact with the first mentioned dehydrocyclizing catalyst.

25 3. A process for producing a substantially olefin-free aromatic hydrocarbon fraction which comprises contacting aliphatic hydrocarbons including paraffins and olefins of 6-12 carbon atoms per molecule with a dehydrocyclizing cat-

30 alyst at a temperature in the approximate range of 850-1200° F. under a pressure from substantially atmospheric to approximately 100 pounds per square inch to form a product comprising essentially aromatic, olefinic, and paraffinic hy-

35 drocarbons; extracting said product by a selective solvent to separate a substantially paraffinic raffinate from a mixture comprising essentially olefinic and aromatic hydrocarbons; recycling said raffinate to contact with the original dehydro-

40 cyclizing catalyst; and subjecting said mixture of olefinic and aromatic hydrocarbons to contact with a separate dehydrocyclizing catalyst under independently controlled conditions of temperature and pressure to produce a substantially olefin-free aromatic product.

45 4. A process for producing a substantially olefin-free aromatic hydrocarbon fraction which comprises contacting aliphatic hydrocarbons including paraffins and olefins of 6-12 carbon atoms per molecule at a temperature in the approximate range of 850-1200° F. under a pressure from substantially atmospheric to approximately 100 pounds per square inch for a time of contact of

50 55 a composite of 98-75% by weight of activated alumina and 2-25% by weight of chromium sesquioxide to form a product comprising essentially aromatic, olefinic, and paraffinic hydrocarbons; extracting said product by liquid sulphur dioxide to separate a substantially paraffinic raffinate from a mixture comprising essentially olefinic and aromatic hydrocarbons; recycling said raffinate to contact with the original dehydrocyclizing catalyst; and subjecting said mixture of olefinic

60 65 and aromatic hydrocarbons at a temperature in the approximate range of 850-1200° F. under substantially atmospheric pressure for a time in the approximate range of 1-100 seconds to contact with a separate composite of 98-75% by weight of activated alumina and 2-25% by weight of chromium sesquioxide to produce a substantially olefin-free aromatic product.
